Application March 25, 1947, Serial No. 736,994

3 Claims. (Cl. 62—1)

1

This invention relates generally to valves and more particularly to an improved valve or fitting for use in conjunction with containers of liquefied petroleum gases.

Petroleum products such as butane, propane, butylene, propylene and various mixtures thereof are commonly stored in containers under pressure in both the liquid and vapor phases, the vapor being in equilibrium with the liquid. These substances in their vapor phases are generally used as fuel, particularly in rural areas where piped gaseous fuels such as natural gas or producer gas are not available. Relatively pure liquid propane and a mixture of liquefied butane and propane known as commercial butane are in widest use at the present time.

In general, two types of gas systems are employed. The first type which is more adaptable to the needs of consumers using large volumes of gas comprises a large immovable tank equipped with conduits and pressure regulators. This tank is filled from time to time with liquefied petroleum gas from tank trucks which transport the gas from bulk storage plants to the consumer.

The second type of system is more readily adaptable to the smaller consumer. Here cylinders holding approximately five cubic feet of liquid are filled at the bulk storage plant and delivered by truck to the consumer to be attached to his service line through a pressure reducing regulator. When a container becomes empty it is replaced by a full one and the empty is returned to the distributor for refilling.

The valve or fitting of this invention is particularly intended for use with the latter type of system but may also be used on permanent tank installations with advantage.

Valves currently used on cylindrical gas containers usually comprise a brass or bronze body threaded at one end and received in an opening at the top of the container. A passage through the body leads from the inside of the cylinder to a valve port. A movable valve member attached to a rotatable handle coats with this port to control the flow of gas therethrough, and a second passage extends from the downstream side of the port to an outlet connection where the service line is attached. A spring loaded pressure relief safety valve is in communication with the passage leading from the inside of the container and allows gas to escape from the container should the pressure rise above a predetermined limit. Such a valve is disclosed in the copending application of Savin L. Sundstrom

2

et al., Serial No. 698,171, filed August 8, 1946, reference to which is hereby made.

When a mixture of liquid hydrocarbons such as commercial butane is allowed to evaporate in a container by withdrawing vapor, the more volatile constituent, in this case propane, will tend to vaporize first leaving the liquid richer in the less volatile constituent, butane. Thus the vapor withdrawn will not have a uniform composition and, therefore, will not have a uniform heating value. One way of overcoming this disadvantage is to educt liquid, rather than vapor, from the container and vaporize it by supplying heat units and reducing the pressure. This procedure is quite generally followed in large permanent tank installations, but has not been much employed in the small replaceable cylinder systems, because of the limitations imposed by the presently used cylinder valves.

20 If a cylindrical container is filled with liquid, beyond a certain safe point, and then allowed to become warmer, the expansive force of the liquid will be added to the increased pressure of the vapor with the result that either the pressure relief valve will open, with resultant loss of fuel and danger of fire, or the container may burst. The present practice is, therefore, to carefully weigh the amount of liquid charged into a container stopping the filling operation when the 25 danger limit is reached. This is, however, a difficult procedure and is frequently subject to error.

One object of the present invention is to provide a cylinder valve having a vent tube of small cross sectional area which extends down into the cylinder to the safe fill level and through which liquid will be forced when the safe limit of filling is reached to give a visual indication to the person charging the cylinder that it has been 30 filled to the safe limit.

Another object of this invention is to provide a unitary fitting having a back check filler valve, a spring loaded pressure actuated safety valve, a manually controlled service valve, a fusible 35 plug for releasing pressure should the temperature rise above a certain point, and a vent tube which will indicate overfilling of the container.

Another object is to provide a fitting having a unitary body which may be economically formed 40 from forged as well as cast metal.

Another object is to provide a compact fitting in which the pressure actuated safety valve opens in an upward direction so that the cylindrical container will not be upset by back pressure if the 45 safety valve functions.

Another object is to provide a compact fitting having a boss thereon inclined upwardly at a convenient angle for attachment of the filling conduit.

Another object is to provide an eduction tube extending from the fitting to a point inside the container so that when used in the tank of a vapor eduction system incoming liquid will not mix with the vapor being withdrawn.

Another object is to provide a fitting having an eduction tube extending to a point within the container so that either a liquid eduction or vapor eduction system may be formed by merely altering the length of the tube, the same fitting being used in either case.

Other and additional objects will be apparent to those familiar with the art on reading the following specification in conjunction with the drawings and the appended claims.

In the drawings:

Fig. 1 is a section of a cylindrical container showing the manner in which the fitting of this invention is installed.

Fig. 2 is a section showing the fitting installed in a cylindrical container modified for vapor eduction.

Fig. 3 is a top view of the fitting of this invention.

Fig. 4 is a vertical section taken on line 4-4 of Fig. 3.

Fig. 5 is a vertical section taken on line 5-5 of Fig. 3.

The cylinder valve or fitting 10 is shown in Fig. 1 to be installed in a cylindrical container 11 containing liquid 12 in equilibrium with vapor 13. The fitting 10 comprises a forged or cast body 14 provided with a pipe thread 15 at its lower end for supporting it in a threaded opening 16 in the top of the cylinder 11. A second thread 17 is machined on the body 14 above the pipe thread 16 and supports a nut 18. A sealing gasket 20 (Figs. 4 and 5) carried by the nut 18 serves to form a pressure tight seal between the top of the cylinder 11 and the body 14 when the nut 20 is screwed downwardly.

The body 14 approximates the shape of the capital letter "Y," two bosses 21 and 22 inclined at an angle from the vertical being provided thereon. Two horizontal bosses 23 and 24, diametrically spaced on opposite sides of the body 14, are also provided. A passage 25 extends from the bottom of the body 14 upwardly to the middle where it connects with a passage 27 extending into the boss 21 and a passage 28 extending into the boss 22. The boss 21 is hollowed out to form a cavity 30 connected to the passage 27 and the boss 22 has a cavity 31 connected to the passage 28. Thus the interior of the container 11 is in communication with the two cavities 30 and 31.

The cavity 30 contains a filler valve assembly similar to that disclosed in Patent No. 2,361,866 issued to H. L. Norway on October 31, 1944, reference to which is hereby made. The upper end of the cavity 30 is provided with a female thread 32 which receives a ring 33 having a conical valve seat 34. A valve member 35, within the cavity 30, is urged against this seat 34 by a spring 36. The sides of the member 35 are provided with flutes 37, and a hole 38 extends through the side wall from each flute 37 to an annular groove 40 cut into the member 35 from the bottom. This provides for free passage of gas past the member 35 when it is moved away from the seat 34.

A blind hole 41 is drilled into the member 35 from its top face for supporting a second valve 39

member 42. This member 42 is urged away from the member 35 by a small spring 43 in the bottom of the hole 41. The top face of the member 42 is hollowed to receive a valve disc 44 held in place by a screw 45.

The valve member 42 is normally held against a seat 46 integrally formed in a cap member 47 which is secured to the end of the boss 21 by a thread 48. An internal thread 51 is provided in the cap member 47 for securing a dirt cap 50. A washer 52 supported in the cap member 47 forms a gas tight seal between the member 47 and the cap 50; and the top of the cap member 47 is provided with a coarse thread 53 to which the fitting conduit (not shown) may be attached.

The boss 22 contains the pressure relief valve mechanism comprising a valve member 55, a spring 56, and a spring retainer 57. The lower face of the member 55 carries an elastomer valve disc 58 which is normally held against the valve seat 60 by the force of the spring 56. In the event that the pressure in the passage 28 exceeds the force of the spring 56, the valve member 55 will be forced away from the seat 60 and allow gas to pass out of the passage 28 by the member 55 to the atmosphere.

The boss 23 contains the service valve mechanism as shown in Fig. 4. A liquid eduction tube or pipe 62 extends from a point adjacent to the bottom of the container 11 into a threaded hole 63 opening into the passage or cavity 25. A short horizontal passage 64 extends from the top of this hole into a cavity 65 in the boss 23 forming a valve port 66.

A bonnet 67 is supported in threads 68 in the cavity 65 and seals the periphery of a flexible diaphragm 70 to the wall of the cavity 65. The bonnet 67 also supports the rotatable valve stem 71. This stem is provided with threads 72 so that rotation of the hand wheel 73, fixed to the stem 71 will move it into or out of the cavity 65. The inner end of the stem 71 is attached to a valve member 75 by the head and socket arrangement indicated at 76 so that longitudinal movement, but not rotation, of the stem is transferred to the member 75. The member 75 is sealed to the diaphragm 70 by a nut 77 and a washer 78 so that the inner portion of the cavity is sealed from the atmosphere by the diaphragm 70. The inner end of the member 75 is threaded to receive a retainer 80 which supports an elastomer valve disc 81 in alignment with the port 66. By this arrangement rotary movement of the hand wheel 73 will open or close the valve port 66.

A horizontal drilled passage 82, disposed to one side and parallel to the passage 64, extends from the cavity 65 through the body to the bottom of a cavity 83 machined into the boss 24. This cavity 83 is provided with threads 85 to which a fitting (not shown) on the end of the service conduit (not shown) may be screwed. Thus the valve 75 controls the flow of liquid 12 from container 11 into the service line.

Another tube 86 extends from a hole 87 inside the body 14, parallel to the tube 62, to a point inside the container 11. The length of the tube 86 is determined by the height of the maximum level to which the cylinder 11 may be filled safely. This is approximately 90% of the full capacity of the container 11 when commercial butane is to be stored. The upper end of the hole 87 is in communication with an inclined passage 88 which extends to the bottom of a threaded hole 90 terminating in a valve port 91. A valve member 92 provided with an elastomer disc 93 is

screwed into the threads 94. A small diameter hole 99 (Fig. 3) connects the bottom of the hole 90 to the atmosphere so that gas or liquid may escape therethrough when the member is unscrewed slightly. A pin 95 of lesser diameter than the passage 88 and supported by the member 92 extends into the passage 88 providing a means to prevent the passage 88 from becoming clogged with foreign particles.

A threaded hole 97 (broken lines in Figs. 4 and 5) extends into the top of the body 14 and receives a threaded plug 98. The bottom of the hole 97 is connected by a passage 100 to the passage 27 and is, therefore, in communication with the inside of the container 11. The center of the plug 98 is drilled out and filled with an alloy 101 which melts in the neighborhood of 212° F. Thus if the temperature of the fitting 10 and container 14 should rise above 212° F. the fuze metal 101 will soften and be forced out of the plug 98 allowing the contents of the cylinder 11 to escape to the atmosphere.

The modified fitting 10a shown in Fig. 2 is similar to the fitting 10 described above except that a short eduction tube 62a is substituted for the long liquid eduction tube 62. By employing the short tube 62a, a vapor eduction system results, for this tube 62a is somewhat shorter than the vent tube 86, and in practice the cylinder 11 would not be filled to a level above the bottom of the tube 86. In some instances the tube 62a may be eliminated entirely to produce a vapor eduction system, but, if this is done, the fitting 10a may not be used in permanent tank systems which are operated continuously. By employing the short tube 62a, the danger of incoming liquid, as the tank 11 is filled, mixing with the outgoing vapor is eliminated. To insure that liquid draining down the tube 62a will not be sucked into the mouth of the tube 62a, a slight flare 103 is provided on the bottom serving to deflect the liquid outwardly from the mouth of the tube 62a. A similar flare 89 on the tube 86 performs the same function to prevent a false indication.

The operation of this fitting 10 is as follows: Assuming that the container 11 is empty and is about to be filled at a bulk storage plant, the dirt cap 50 is first removed, and a filling conduit (not shown) is screwed onto the threads 53 making a seal against the washer 52. Liquid under pressure is then allowed to flow through the filling conduit, the pressure first overcoming the force of the spring 43 to move the member 42 away from the seat 46. As soon as the member 42 has been lifted away, pressure acts against the member 35 moving it downwardly away from the conical seat 34, and the liquid flows past the member 35 into the space between the flutes 31. From this space it then flows inwardly through the hole 38, into the annular space 40, and then through the passages 27 and 25 to the container 11.

The vent valve member 92 is opened during the filling operation and air or vapor in the container 11 passes out through the tube 86 and the passages 87 and 88, flowing through the small hole 99 to the atmosphere. As the container 11 fills, the level of the liquid 12 rises until it reaches the bottom of the tube 86. When this occurs, liquid 12 rather than vapor 13 passes up the tube 86 to emerge around the member 92 and give a visual as well as audible signal that the cylinder 11 has been filled to the safe limit. The flow through the filling conduit (not shown) is then shut off and pressure within the container moves

the valve members 35 and 42 against their respective seats when the conduit is disconnected. After the dirt cap 50 has been replaced, the cylinder 11 may be transported to the place where gas is to be consumed.

A service conduit (not shown) is then connected in the hole 83 in the boss 24. The hand wheel 73 may then be rotated manually moving the stem 71 outwardly. As the stem 71 moves, it carries the valve member 75 with it, lifting the disc 81 away from the port 66. Pressure of the vapor 13 inside the container then forces liquid 12 to flow upwardly through the tube 62, out of the port 66, and into the cavity 65. From the cavity 65 it flows through the horizontal passage 82 and into the service conduit (not shown). This flow of liquid out of the container will then continue as gas is consumed until the member 75 is again moved to close the port 66 or the container becomes emptied.

The method by which the disc 81 is fastened to the valve member 75 results in an advantage not found in conventional cylinder valves. Should it be required to replace the disc 81 the bonnet 67 is unscrewed to remove the valve member 75 from the body 14 and the retainer member 80 is unscrewed, carrying the disc 81 with it. This disc 81 is then pushed out from behind and a new one pushed in. The retainer member 80 is then screwed back onto the member 75 and the member reinstalled in the body 14. In a similar manner the diaphragm 70 may be readily replaced by removing the nut 77.

From the foregoing it will be apparent to those familiar with the art that a novel fitting or cylinder valve of considerable utility has been provided which greatly simplifies the filling operation when used on conventional containers for liquefied gas and which has additional safety features not found on presently used equipment.

It is not intended that this invention be limited to liquefied petroleum gases for it could be employed for other liquids or gases as well. It will also be apparent to those familiar with the art that various changes and modifications in the described embodiment may be made without departing from the spirit of the invention whose scope is defined by the following claims.

What is claimed is:

1. In combination a container and a fitting received in an opening in the top of the container, said fitting comprising a body, a pair of inclined bosses integral with said body, a bifurcated passage extending through said body from a point inside of said container to the bottom of a cavity in each of said inclined bosses, a backflow check valve received in one of said bosses for sealing one branch of said bifurcated passage, a spring loaded pressure actuated safety relief valve received in the other of said inclined bosses, a pair of horizontal bosses disposed diametrically on opposite sides of said body and having cavities therein, a valve port opening into the cavity in one of said bosses, a tube supported in said body extending from the common branch of said bifurcated passage to a point within said container, another passage connecting the end of said tube to said valve port, a movable valve member received in one of said horizontal bosses for closing said valve port, and a passage connecting the cavities in each of said horizontal bosses.
2. In combination a container and a fitting received in an opening in the top of the container, said fitting comprising a body, a pair of inclined bosses integral with said body, a bifurcated pas-

sage extending through said body from a point inside of said container to the bottom of a cavity in each of said inclined bosses, a backflow check valve received in one of said bosses for sealing one branch of said bifurcated passage, a spring loaded pressure actuated safety relief valve received in the other of said inclined bosses, a pair of horizontal bosses disposed diametrically on opposite sides of said body and having cavities therein, a valve port opening into the cavity in one of said bosses, a tube supported in said body extending from the common branch of said bifurcated passage to a point adjacent the bottom of said container, another passage connecting the end of said tube to said valve port, a movable valve member received in one of said horizontal bosses for closing said valve port, and a passage connecting the cavities in each of said horizontal bosses.

3. For use in a fitting, a filler valve comprising a cylindrical passage having a shoulder at one end and an inwardly facing conical seat at the other, a valve member substantially filling and

disposed within said passage, means for urging said member toward said conical seat, an annular groove opening into said member from the end opposite said seat, a plurality of flutes on the sides of said member for supporting said member in said passage, a radial hole connecting each flute with said annular groove, a second valve seat coaxial with said conical seat, and a second valve member supported by said first member but movable independently therefrom for closing against said second seat.
